Silas McClure Inventor

By his Attorney's

Pennie Davis Marvin & Edwards

UNITED STATES PATENT OFFICE.

SILAS MCCLURE, OF BEAVER DAM, WISCONSIN.

LATCH FOR OVEN DOORS.

1,413,990.

Specification of Letters Patent. Patented Apr. 25, 1922.

Application filed December 1, 1920. Serial No. 427,470.

To all whom it may concern:

Be it known that I, SILAS MCCLURE, a citizen of the United States, residing at Beaver Dam, in the county of Dodge, State of Wisconsin, have invented certain new and useful Improvements in Latches for Oven Doors; and I do hereby declare the following to be a full, clear, and exact description of the invention, such as will enable others skilled in the art to which it appertains to make and use the same.

This invention relates to oven doors, and has for its object the provision of an inexpensive and reliable latch or fastening which is wholly concealed between the door and the stove when the stove is closed, and which holds the door securely closed and is released by moving the door bodily in the plane of the door, and which includes means for releasing the door when undue stress is exerted on the door in a direction to open the same. A further object of the invention is to provide a fastening operated without shock or jar which might injure the contents of the oven.

Further objects and advantages of the invention will be apparent as it is better understood by reference to the following specification and the accompanying drawing, illustrating the preferred embodiment, in which—

Fig. 1 is a view in elevation of a stove to which my invention is applied;

Fig. 2 is a vertical transverse section through the catch; and

Fig. 3 is a section on the line 3—3 of Fig. 2.

It is particularly desirable, in gas stoves, to provide a simple and effective fastening for the oven door, which will be automatically released by pressure developed through explosion of accumulated gas in the oven and numerous more or less clumsy contrivances have been suggested and used in an attempt to accomplish the desired object.

Gas stoves have reached a high stage of perfection, and, to meet the demands of a critical public, much attention is directed to the outward appearance of the stove by progressive manufacturers. Obviously, therefore, a fastening which disfigures the stove will not find favor with the manufacturer; nor will the public accept a stove with accessories which fail to produce a pleasing appearance.

With the purpose in view of producing a fastening which is mechanically satisfactory and at the same time entirely concealed when

the oven door is closed, I have devised the present invention. Briefly the invention involves the use of a knob which is secured to the stove frame and is provided with two 60 preferably frusto-conical faces, in cooperation with a member concealed within the door frame and having an opening through which the knob projects when the door is closed. The parts mentioned are immovable 65 with respect to the stove and door frames upon which they are supported and the door is loosely supported on its hinges which provide sufficient play to permit the knob to enter the opening, the lip at the edge thereof 70 normally providing a secure fastening which holds the door in closed position. As will be apparent the parts are all rigid and therefore strong and serviceable. The weight of the door is sufficient to prevent accidental 75 opening. The lip, however, engages a frusto-conical surface when force is applied to the door to close or open it and riding over this surface lifts the door the required distance without effort by the operator. Force applied 80 by an explosion within the oven immediately opens the door and serious damage to the stove is prevented.

Referring to the drawing, 5 indicates the body of a stove which in the present instance 85 is a combination coal and gas range although my invention is obviously not restricted to this particular type of stove. An oven door 6 is supported on hinges 7 which as above pointed out permit a vertical movement of 90 the door. A comparatively slight play is sufficient and may be accomplished by enlarging the openings for the hinge pintles in one of the members of each hinge. The door comprises a channel shaped frame 8 95 preferably of malleable iron, a sheet metal back or lining 9, and a sheet metal panel 10 which is preferably enameled. A handle 11 is secured to the door to facilitate opening and closing thereof.

Concealed within the frame 8, preferably at the center of its upper side is a sheet metal member 12 roughly U-shaped and having one arm riveted as indicated at 12', or otherwise fastened to the frame 8. The 105 other arm is provided with an opening 13 which is thus surrounded by a lip, adapted to cooperate with a knob 14 on the stove frame.

The knob 14 is preferably in the form of 110 a rivet having an end 15 which is inserted in a suitable opening provided in an angle

iron 16 which is a part of the stove frame. The end 15 has a shoulder which is adapted to bear against the outer surface of the stove, while the rivet is battered to secure the knob 14 in place. The knob 14 preferably has outer and inner frusto-conical faces 17 and 18 and an intermediate cylindrical portion although the form of the knob may be varied.

In closing the door pressure is applied to the handle 11 or the door given sufficient momentum to ensure that the lip above the opening 13 rides up the conical surface 17 and drops behind the cylindrical portion of the knob, the door being slightly lifted on its hinges during this operation. A pull on the handle causes the lip to similarly ride up the conical surface 18 and drop on the other side of the cylindrical portion of the knob. An explosion within the oven opens the door 20 exactly as if the handle had been pulled.

The simplicity and neatness of the catch is sufficiently obvious. It is easily manufactured and applied and is, therefore, inexpensive. The oven door is securely held except when opened in the manner described and the parts are of a kind which are not easily damaged even by abusive treatment. These and other advantages of my invention insure its successful and satisfactory use in gas stoves and the like.

Various changes may be made in the form, arrangement and construction of the parts without departing from the invention or sacrificing any of its attendant advantages.

35 I claim:

1. An improvement in stoves comprising an oven door hingedly supported on the stove to swing with respect thereto, and to move bodily in the plane of the door, and cooperating means on the stove and door to hold the door closed and to move the door bodily in its plane when opened or closed to engage and release the holding means.

40 2. An improvement in stoves comprising an oven door hingedly supported on the stove, and susceptible of bodily movement in the plane of the door, a knob on the stove, and means secured on the inner face of the door and adapted to cooperate with the knob to hold the door in closed position, said means and knob having engaging surfaces for moving the door bodily in the plane thereof when it is opened or closed, whereby pressure within the oven will release the 50 holding means.

55 3. An improvement in stoves comprising an oven door having a channel-shaped frame, which is hingedly supported on the stove and susceptible of bodily movement in the plane of the door, a knob on said stove having sloping inner and outer surfaces and a member concealed in said frame and adapted

to cooperate with the knob to hold said door in closed position and released by such bodily movement of the door.

4. An improvement in stoves comprising an oven door having a channel-shaped frame, which is hingedly supported on the stove and susceptible of bodily movement in the plane of the door, a knob on said stove having sloping inner and outer surfaces and a member concealed in said frame and provided with an opening to receive said knob and a lip which cooperates with said knob to hold said door in closed position and released by such bodily movement of the door.

5. An improvement in stoves comprising an oven door having a channel-shaped frame, which is hingedly supported on the stove and susceptible of bodily movement in the plane of the door, a knob on said stove having inner and outer frusto-conical surfaces and a sheet metal member concealed in said frame and provided with an opening to receive said knob and a lip which cooperates with said knob to hold said door in closed position and released by such bodily movement of the door.

6. An improvement in stoves comprising a door, hinged to the stove to swing into and out of closed position and to move bodily with respect to the stove in the plane of the door toward and from the hinged connection, means between the stove and the door and concealed when the door is closed for holding the door closed, and releasable by the bodily movement of the door away from the hinged connection.

7. An improvement in stoves comprising a door hinged to the stove to swing into and out of closed position and to move bodily with respect to the stove in the plane of the door toward and from the hinged connection, means between the stove and the door and concealed when the door is closed for holding the door closed and releasable by the bodily movement of the door away from the hinged connection, and having means for releasing the door when undue pressure is exerted on the door in a direction tending to open the same.

8. An improvement in stoves comprising a door hinged to the stove to swing toward and from the stove and to move bodily in the plane of the door toward and from the hinged connection, means for holding the door closed and released by the bodily movement of the door away from the hinged connection and having means for so moving the door to release the holding means when pressure is exerted upon the door from within the stove.

In testimony whereof I affix my signature.
SILAS McCLURE.
